Primary Examiner — Carla Jobe Wright(74) *Attorney, Agent, or Firm* — Birch, Stewart, Kolasch & Birch, LLP(57) **CLAIM**

The ornamental design for a mobile phone case, as shown and described.

DESCRIPTION

FIG. 1 is a perspective view of the interior of a mobile phone case in an open configuration showing our new design;

FIG. 2 is an elevation view of the interior thereof;

FIG. 3 is an elevation view of the exterior thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front perspective view thereof in a closed configuration.
The broken lines depict environmental subject matter that forms no part of the claimed design.**1 Claim, 7 Drawing Sheets**FIG. 1

FIG. 2
